UNITED STATES PATENT OFFICE

2,420,464

SHOEMAKING

Anthony Cocozella, Lynn, Mass.

Application December 29, 1945, Serial No. 638,017

2 Claims. (Cl. 12—142)

1

This invention consists in an improved process of manufacturing shoes of the platform type disclosed in my prior Letters Patent No. 2,370,937, dated March 6, 1945. Shoes of this type are now being manufactured in more extreme styles than heretofore, and the object of the present invention is to provide an economical and convenient process of manufacturing a platform shoe of streamline appearance having pronounced arch curvature and carrying a heel of substantial height.

A shoe made in accordance with the process of my invention is characterized by a binding strip of leather or ornamental fabric attached at one edge to the margin of a stiff and substantial insole or platform sole. The binding strip is wrapped around the outer edge of this sole and secured in place with its inturned edge concealed beneath the outsole. The outturned margin of the upper is also secured to the platform sole. There are very substantial advantages in attaching the upper and the binding strip, or platform cover, directly to the platform sole rather than to a flexible sock lining. If the upper and binding strip are attached in the first instance to a sock lining, an opportunity is introduced for inaccuracy in subsequently locating the platform sole. This results in a serious defect in the appearance of the shoe. All of such dangers are obviated by the characteristic step of my process of first stitching the marginal edge of the upper and the binding strip to a platform sole of substantial thickness and appreciable stiffness as compared to a sock lining.

In the manufacture of high style shoes it is sometimes desired to employ a platform in the forepart of the shoe which is too thick to be conveniently stitched. Going more into detail, it is an object of my invention to provide a process wherein a platform of pronounced thickness may be employed and the advantages of direct stitching preserved. I have discovered that these desirable results may be achieved by stitching the marginal edge of an upper directly to a platform sole of substantial but not of excessive thickness, that is, a platform sole about $\frac{1}{8}$ of an inch thick, attaching one edge of a binding strip to the said sole, preferably by stitches passing through the margin of the upper and the sole itself, then locating on the outer face of the said sole a midsole or a platform section at least the same thickness as the already attached sole, trimming the edges of both soles so that they present an unbroken peripheral surface, and finally wrapping the binding strip about the edge of the combined

2

soles. By this procedure the stitching operation may be conveniently carried out upon a platform sole of moderate thickness such as operators are now used to handling, and then after the stitching operation, the platform may be built up to any desired thickness and then covered in the same manner in which the operator has become skilled in covering the edges of platform soles.

These and other advantages of the invention 10 will be best understood and appreciated from the following description of a preferred manner of putting it into effect, illustrated in the accompanying drawings in which:

Fig. 1 is a fragmentary view in perspective, 15 partly in section, illustrating the step of attaching the upper to a platform sole,

Fig. 2 is a similar view illustrating the second 20 step of the process, that is to say, attaching the binding strip,

Fig. 3 is a view in perspective suggesting the 25 operation of evening the edges of the assembled platform sole sections,

Fig. 4 is a fragmentary sectional view on an 30 enlarged scale, and

Fig. 5 is a view in elevation of the forepart and 35 shank of the finished shoe.

In carrying out the process of my invention as 40 herein illustrated, an insole, or a platform sole, or other sole piece 10 is first selected from any desired platform sole stock, substantial in thickness and appreciably stiff in texture. Platform sole material comprising a ground cork composition in sheet form is now available in the shoemaking industry, and this may be cut or died out in the proper shape for the platform for the sole to be manufactured. The platform sole 10 is herein shown as shaped with a square marginal edge, but this may be slightly inclined if desired. The upper 12 is completed with or without a 45 lining as desired and cut accurately according to pattern.

The first step of the process may be carried 50 out with the assistance of a straight needle sewing machine as suggested in Fig. 1 where the bed 45 14 of the machine supports the platform sole 10 and a roller gauge 16—18 guides the marginal edge of the platform sole 10 in a path beneath the needle bar 28 such that a stitchline 21 is formed parallel to and adjacent to the marginal edge of the sole 10. This line of stitching passes through the outturned margin of the upper 12 and through the full thickness of the platform sole 10, as clearly shown on a larger scale in 55 Fig. 4. The edge gauge is rotatably mounted on a sewing machine bed 14 and comprises a freely

rotatable roll 16 and a freely rotatable concentric ring 18 which surrounds the roll 16 and provides effective gauging surface against which the edge of the platform sole is held.

In carrying out the second step of my novel process, one edge of the binding strip 22 is brought into registration with the previously attached edge of the upper 12, the ring 18 is removed from the gauge, and the platform sole 10 is advanced in a path gauged by the roller 16, while a second row of stitching 23 is formed parallel to and slightly within the previously formed stitchline 21. It will be understood that since the effective diameter of the gauge 16 is less than the effective diameter of the gauge 16-18, a wider edge extension is provided beneath the needle bar 20 in carrying out the second step of the process than in carrying out the previous stitching step.

Having attached the upper and binding strip to the platform sole 10 as above explained, the partially formed shoe is inverted and a midsole section or half sole 24 is accurately located upon the forepart of the platform sole 10 and secured thereto by cement or other adhesive. The section 24 is coextensive with the forepart of the platform sole and is provided with a long beveled surface at its rear edge. The forward edge of this beveled section should coincide substantially with the ball line of the finished shoe and the beveled portion will be incorporated smoothly in the shank of the finished shoe. Having permanently attached the midsole section 24, the edges of both sections are trimmed so that they present an unbroken peripheral surface. There is, of course, not much material that needs to be removed in this step and satisfactory results may be secured by presenting the combined edges to a sandpaper roll 28 as shown in Fig. 3.

Having now built up the forepart of the platform sole, it remains only to cover the composite edge surface of the resulting sole by wrapping the binding strip 22 outwardly, drawing it tightly over the edge surface, and turning its margin inwardly over or beneath the surface of the midsole section or of the platform sole 10, whichever is exposed in the shoe bottom. In this operation the binding strip encloses and conceals the raw edge of the upper as well as both stitchlines 21 and 23, the peripheral surfaces of the platform sole 10 and the midsole section 24. The two lines of stitching are herein shown as being made of thread of substantially the same weight, but if desired a lighter thread or a longer stitch may be used in securing the upper alone to the platform sole than is used for attaching the binding strip and the upper in the inner line of stitching 23.

A last may be inserted in the shoe at any convenient stage of its manufacture. It is contemplated that at the most convenient time a last may be forcibly inserted and the insole conformed to its contour by steps usually followed in the manufacture of such shoes. A steel shank may be inserted at the proper time in order to maintain permanently the curvature of the shank.

The shoe is completed by cementing an outsole 30 in place, shaping it to the longitudinal curvature of the shoe bottom, and uniting it to the lower face of the platform sole and of the midsole section 24. The outsole, of course, conceals the line of juncture between the beveled surface of the midsole and the platform sole and smoothly follows the contour of the composite shoe bottom thus provided. In the finished shoe the effect is secured of a thick platform in the forepart merging smoothly into a shank of reduced thickness, and thus are achieved the stylized lines so much prized in shoes of the type shown in Fig. 5.

Having thus disclosed my invention and described in detail an illustrative process exemplifying it, I claim as new and desire to secure by Letters Patent:

1. The process of making platform shoes, which includes the steps of stitching the marginal edge of an upper directly to a platform sole about $\frac{1}{8}$ of an inch in thickness, attaching one edge of a binding strip to the said sole by stitches passing through the margin of the upper and the sole itself, locating on the outer face of the said sole a midsole of at least the same thickness as the already attached sole, the midsole terminating in a beveled portion at its rear edge, attaching the midsole with its beveled portion adjacent to the ball line of the platform sole so that the beveled portion will be incorporated in the shank of the finished shoe, trimming the edges of both soles so that they present an unbroken peripheral surface, and then wrapping the binding strip about the edge of the combined soles throughout the forepart of the shoe.

2. The process of making platform shoes, which includes the steps of stitching the marginal edge of an upper directly to a full length platform sole of substantial thickness, stitching one edge of a binding strip to the attached edge of the upper, cementing a half sole also of substantial thickness to the outer face of the already-attached sole so as to present a beveled edge at the shank of the shoe, evening the edges of both soles simultaneously so that they present a smooth composite peripheral surface, and then wrapping the binding strip about the edge of the combined soles in the forepart of the shoe and about the edge of the full length platform sole in the shank and heel-seat portions of the shoe.
